(57) **CLAIM**

The ornamental design for a melter system as shown and described.

DESCRIPTION

FIG. 1 is a top front left side perspective view of a melter component of a melter system according to a first embodiment;

FIG. 2 is a left side elevation view thereof;

FIG. 3 is a right side elevation view thereof;

FIG. 4 is a front end elevation view thereof;

FIG. 5 is a rear end elevation view thereof;

FIG. 6 is a top end plan view thereof; and

FIG. 7 is a bottom end plan view thereof.

FIG. 8 is a top front left side perspective view of a melter system according to a second embodiment;

FIG. 9 is a left side elevation view thereof;

FIG. 10 is a right side elevation view thereof;

FIG. 11 is a front end elevation view thereof;

FIG. 12 is a rear end elevation view thereof;

FIG. 13 is a top end plan view thereof; and

FIG. 14 is a bottom end plan view thereof.

FIG. 15 is a top front left side perspective view of a melter component of a melter system according to a third embodiment;

FIG. 16 is a left side elevation view thereof;

FIG. 17 is a right side elevation view thereof;

FIG. 18 is a front end elevation view thereof;

FIG. 19 is a rear end elevation view thereof;

FIG. 20 is a top end plan view thereof; and

FIG. 21 is a bottom end plan view thereof.

The broken lines are for the purpose of showing environmental structure and form no part of the claimed design.
